Primary Examiner — Robin V Webster*(74) Attorney, Agent, or Firm* — Robert Curcio; De Lio, Peterson & Curcio, LLC(57) **CLAIM**

The ornamental design for a filter cartridge with flange end, as shown and described.

DESCRIPTION

FIG. 1 is the front perspective view of the filter cartridge with flange end according to the present invention;
FIG. 2 is the back perspective view of the filter cartridge with flange end of FIG. 1 according to the present invention;
FIG. 3 is the left side view of the filter cartridge with flange end of FIG. 1 according to the present invention;
FIG. 4 is the right side view of the filter cartridge with flange end of FIG. 1 according to the present invention;
FIG. 5 is the top view of the filter cartridge with flange end of FIG. 1 according to the present invention;
FIG. 6 is the bottom view of the filter cartridge with flange end of FIG. 1 according to the present invention;
FIG. 7 is the front view of the filter cartridge with flange end of FIG. 1 according to the present invention; and,
FIG. 8 is the back view of the filter cartridge with flange end of FIG. 1 according to the present invention.
